UNITED STATES PATENT OFFICE

162,127

CHINA STAND

Albert Chicorel, Detroit, Mich.

Application November 7, 1950, Serial No. 12,896

Term of patent 14 years

(Cl. D44—10)

To all whom it may concern:

Be it known that I, Albert Chicorel, a citizen of the United States of America, residing at Detroit, in the county of Wayne and State of Michigan, have invented a new, original, and ornamental Design for a China Stand, of which the following is a specification, reference being had to the drawing, forming a part thereof.

The dotted line showing of a cup and saucer is merely for the purpose of illustration.

I claim:

The ornamental design for a china stand, substantially as shown and described.

ALBERT CHICOREL.
